(57) **CLAIM**

The ornamental design for a bottle, as shown and described.

DESCRIPTION

FIG. 1 is a top, front, right perspective view of a bottle showing our new design;

FIG. 2 is a front view thereof, wherein the rear view is a mirror image of FIG. 2;

FIG. 3 is a right side view thereof, wherein the left side view is a mirror image of FIG. 3;

FIG. 4 is a top view thereof; and,

FIG. 5 is a bottom view thereof.

Portions of the claimed design are shown separated and bound by a bracket to indicate indeterminate length. The broken lines immediately adjacent to the shaded area represent unclaimed boundaries of the design. The broken lines showing the remainder of the bottle are for illustrative purposes only and form no part of the claimed design.
